APPARATUS FOR TRUING OUT-OF-ROUND CAN BODIES

John Drygulski, Hillside, N. J., assignor to American Can Company, New York, N. Y., a corporation of New Jersey

Application November 8, 1947, Serial No. 784,921

5 Claims. (Cl. 153—32)

1

The present invention relates to apparatus for truing container or can bodies and has particular reference to rounding-up cylindrical can bodies which have been deformed into an out-of-round condition during handling.

In the handling of cylindrical cans preparatory to filling them with a product, the open end of the cans sometimes become bent into an oval or otherwise out-of-round condition and thus prevents proper fitting and sealing of the covers onto the cans after filling. This is partly due to the fact that the open end of the can is not as strong and rigid as its bottom, because the bottom of the can is reenforced by the end closure member which is secured thereto. Such out-of-round cans when encountered in a batch of round cans being fed automatically into the customary filling and sealing machines are the source of considerable trouble since they jam and sometimes cause damage to the machines when the covers cannot be properly fitted into place and secured to the cans.

The present invention contemplates overcoming this difficulty by the provision of apparatus for reforming out-of-round cans into a properly rounded or trued condition preparatory to filling and sealing.

An object of the invention is the provision of apparatus for truing cans wherein the cans are rotated while pressure is applied to the distorted portion of the cans for reforming them to a truly rounded condition so that the covers of the cans will properly fit into place on the cans after filling so as to insure proper sealing of the cans.

Another object is the provision of such apparatus for truing cans wherein out-of-round cans having flanges formed on their open ends may be effectively reformed into a true rounded condition for application of their covers thereto.

Another object is the provision of such apparatus for truing cans wherein simplicity of operations in the structure of the apparatus insure economical and highly efficient results under high speed rates of production.

Numerous other objects and advantages of the invention will be apparent as it is better understood from the following description, which taken in connection with the accompanying drawings, discloses a preferred embodiment thereof.

Referring to the drawings:

Figure 1 is a side elevation of an apparatus embodying the instant invention, with parts broken away;

Fig. 2 is a vertical section taken substantially along the line 2—2 in Fig. 1, with parts broken away;

2

Figs. 3 and 4 are enlarged sectional details of the apparatus illustrated in Fig. 1 and showing a can in place, Fig. 4 showing the can before being reformed into a true rounded condition, and Fig. 3 showing the can after being reformed;

Fig. 5 is a fragmentary elevation of a modified form of the apparatus disclosed in Fig. 1; and

Fig. 6 is a sectional detail of the modified form of apparatus, the view showing an out-of-round can in place in the apparatus for truing.

As a preferred embodiment of the instant invention the drawings illustrate apparatus for truing out-of-round cylindrical sheet metal containers or cans A comprising a tubular body B (Figs. 3 and 4) having a bottom C secured thereto at one end in a suitable end seam D and having its opposite end open and formed with a flange E for the reception of a cover after the container is filled with a product. In truing these out-of-round cans, the cans are rotated on their longitudinal axes and while so rotated, pressure is exerted diametrically against their out-of-round portion. This pressure squeezes a can along its major diametrical axis, slightly beyond its elastic limit and thereby causes the can to take a permanent set substantially equal to the true diameter of the can.

In the drawings, Figs. 1, 2, 3 and 4 illustrate a preferred form of apparatus for truing out-of-round can bodies. This apparatus includes a pair of spaced and parallel wheels which constitute a driving wheel 11 and a truing wheel 12, which are formed on a hub 13 mounted on a driving shaft 14 journaled in bearings 15 carried in a pair of spaced and parallel upright frame members 16 which extend up from a base plate 17. The wheels 11, 12 on their outer peripheries carry a resilient tread 18 made of rubber, leather, or other suitable material for frictionally engaging against a can A to be rotated and trued. This tread may be sunk into a groove 19 in the circumference of the wheels 11, 12 as shown in the drawings, if desired. The wheels 11, 12 are continuously rotated, through the shaft 14, in any suitable manner in a counterclockwise direction as viewed in Fig. 1.

Adjacent the outer periphery of the wheels 11, 12 the apparatus is provided with a pair of spaced and parallel curved stationary rails which constitute a driving rail 22 and a truing rail 23, which are bolted to the base plate 17. These driving and truing rails are disposed in alignment with the peripheries of the driving and truing wheels 11, 12 and extend around the wheels 55 in parallelism therewith for substantially one half of their diameters. The space between the curved

inner face of the driving rail 22 and the outer circumference of the resilient tread 18 on the driving wheel 11 is slightly less than the outer diameter of the end seam D of a can A to be trued so that a can introduced between the wheel and its rail 22 will fit tightly.

The space between the curved inner face of the truing rail 23 and the outer circumference of the resilient tread 18 on the truing wheel 12 is slightly less than the outer diameter of the body B of a can A to be trued, this space being concentric with the space between the wheel 11 and its rail 22, the two spaces having coincident curved center lines.

At their upper ends, the curved truing rails 22, 23 are secured to the upright frame members 16 and project outwardly at an angle beyond these members and thus provide upper inlet chute rails 25 for the introduction of cans A into the apparatus. The chute is completed by a pair of spaced and parallel lower chute rails 26 which are disposed in spaced and parallel relation with the upper chute rails 25 and which are secured to these rails and to the frame members 16. Adjacent the lower ends of the frame members 16, the truing rails 22, 23 terminate in an outwardly and downwardly inclined track 28 for the discharge of the trued cans from the apparatus.

In operation, a continuous procession of cans A, including normally round cans and any out-of-round cans that may be mingled with them, the latter being marked X in Fig. 1, are introduced from any suitable source of supply, into the apparatus by way of the inlet chute rails 25, 26. The cans roll down the inclined chutes on their sides and enter into the space between the driving and truing wheels 11, 12 and their cooperating driving and truing rails 22, 23, with the end seam D of the cans entering between the driving wheel 11 and its rail 22. The resilient tread 18 on the driving wheel 11 frictionally engages against the end seam D of an incoming can and thus presses the seam tightly against the driving rail 22 (see Figs. 3 and 4).

Hence as the driving wheel 11 rotates, it also rotates the can and rolls it along the driving rail 22 with the longitudinal axis of the can in a substantially horizontal position. The driving wheel 11 and its driving rail 22 thus rotate and roll the body of the can through the space between the truing wheel 12 and its cooperating truing rail 23 (see Fig. 4).

During the rotation of the bodies B of the cans A through the truing space between the truing wheel 12 and the truing rail 23, the major diametrical axis of the body of an out-of-round can X is squeezed adjacent the body flange E between the truing wheel and the truing rail to such an extent that the metal of the out-of-round body passes its elastic limit and thereby acquires a permanent set. In this manner, an out-of-round can body as it traverses the truing rail 22 while being rotated is reformed or returned to a substantially true diameter or original shape and is thus in a condition for the reception of its product and a cover. This condition obtains when the can reaches the terminal ends of the driving rail 22 and the truing rail 23 and the can thereupon rolls down the discharge tracks 28 to any suitable place of deposit.

During this travel through the apparatus the cans A are confined against endwise displacement, by guide bars 29 which are disposed at opposite ends of the cans and extend adjacent the path of travel of the cans through the apparatus.

These bars are welded to bracket blocks 30 which are bolted to the rails 22, 23 and the frames 16 at spaced intervals along the lengths of the bars.

In the modified form of the invention as disclosed in Figs. 5 and 6 the cans to be trued or rounded up are interposed between oppositely disposed sets of wheels and rollers which constitute a continuously rotated driving wheel 35 having a resilient tread 36 (Fig. 6), a continuously rotated truing wheel 37 having a resilient tread 38, a pair of idler support or pressure rollers 39 disposed opposite the driving wheel 35 and a set of three truing rollers 40 disposed opposite the truing wheel 37. The support rollers 39 are mounted on short pressure shafts 39' and the truing rollers 40 are mounted on short truing shafts 42. The shafts 39' and 42 are carried in bearings 43 formed on a vertically movable slide 44 which operates in a slide block 45 having a slideway for the slide. The slide block may be a part of the frame of the apparatus. The slide is shifted periodically in any suitable manner for the entrance of a can A into position between the wheels and the rollers and for discharge therefrom.

The driving wheel 35 and the truing wheel 37 preferably are formed as in the preferred form of the invention, on a hub 13 which is mounted on and rotated by a continuously rotating shaft 14. While in the apparatus the cans are retained against endwise displacement by the guide bars 29.

Hence when a can A is in position for truing, the end seam D of the can is in engagement with the resilient tread 36 of the driving wheel 35 and the two support or pressure rollers 39 while the body B of the container extends into the space between the tread 38 on the truing wheel 37 and the three truing rollers 40. Thus, as in the preferred form of the invention, the can is rotated on its longitudinal axis by the driving wheel 35 while the major diametrical axis of the body B adjacent its flange E is squeezed between the truing wheel 37 and the truing rollers 40, to the extent of reforming the body into a true round condition and creating a permanent set in the metal of the body to retain this trued shape.

It is thought that the invention and many of its attendant advantages will be understood from the foregoing description, and it will be apparent that various changes may be made in the form, construction, and arrangement of parts of the apparatus mentioned herein without departing from the spirit and scope of the invention or sacrificing all of its material advantages, the apparatus hereinbefore described being merely a preferred embodiment thereof.

I claim:

1. An apparatus for truing the body wall of an out-of-round sheet metal cylindrical container having a bottom secured to one end in a circular end seam and having its other end open and terminating in a flange, the combination of a rotatable driving wheel having a resilient tread thereon engageable with the circular end seam of said container, a rotatable truing wheel disposed adjacent said driving wheel and having a resilient tread thereon engageable against the body of said container adjacent its terminal flange, and means disposed opposite each of said wheels for maintaining said container in engagement with said driving wheel for rotating said container on its longitudinal axis and for compressing the out-of-round portion of said container adjacent its terminal flange against said truing wheel in the

direction of its major diametrical axis for imparting thereto a permanent set substantially that of the true diameter of the container for reforming the out-of-round flanged container into a truly round container.

2. An apparatus for truing the body walls of out-of-round sheet metal cylindrical containers having circular bottoms, comprising in combination a circular driving rail, a rotatable driving wheel disposed concentric with and in spaced relation to said driving rail for engaging and for rolling the circular bottom of a container along said circular rail, a circular truing rail spaced from said driving rail for engagement with a top open end of said container, and a rotatable truing wheel disposed concentric with and in spaced relation to said truing rail for engaging the body wall adjacent the open end of said rolling container and for pressing the body wall against said truing rail beyond the elastic limit of the material of the container and in the direction of its major diametrical axis to reform the out-of-round container into a round container.

3. An apparatus for truing the body wall of out-of-round sheet metal cylindrical containers having circular bottoms, comprising in combination a circular driving rail, a rotatable driving wheel disposed concentric with and in spaced relation to said driving rail, a circular truing rail disposed adjacent said driving rail for engagement with the open top end of a container, a rotatable truing wheel disposed concentric with and in spaced relation to said truing rail, and means for rotating said driving wheel and said truing wheel in unison said driving wheel rotating the container on its longitudinal axis by rolling its circular bottom along said driving rail and said truing wheel simultaneously pressing the out-of-round body wall of the rolling container adjacent its open end against said truing rail to compress the out-of-round portion of the body wall beyond the elastic limit of the material of the container to impart a permanent set and to reform it into a round container.

4. An apparatus for truing the body walls of sheet metal cylindrical containers having round bottoms and out-of-round open ends, comprising in combination, stationary means constituting a track for rolling containers, said track consisting of a pair of parallel track sections spaced apart a distance approximately the height of said container, rolling means located adjacent said track and having movement parallel to the track for engaging against the periphery of the round bottom of the container to press said bottom against one of said track sections to rotate the container

on its longitudinal axis, and pressure means located adjacent said track and having movement along the track for engaging the wall of the rotating container adjacent its open end to press the container against the second track section to squeeze the out-of-round portion in the direction of the major diametrical axis of the out-of-round container to impart a permanent set substantially that of the true diameter of the container.

5. An apparatus for truing the body wall of an out-of-round sheet metal cylindrical container having a circular bottom secured to one end in a circular end seam, comprising in combination a rotatable drive shaft, a driving wheel mounted on said shaft for engaging peripherally the circular end seam of a container to be trued, a rotatable truing wheel also mounted on said drive shaft adjacent said driving wheel and engageable with the container adjacent an open end thereof including the out-of-round portion of said container, pressure and truing shafts mounted beyond the periphery of said driving and truing wheels parallel to said drive shaft, pressure rollers mounted on said pressure shafts in alignment with said driving wheel for pressing a container in engagement with said driving wheel for rotating said container on its longitudinal axis, truing rollers mounted on said truing shafts in alignment with said truing wheel for pressing the container against said truing wheel to exert pressure on the out-of-round portion of said container sufficient to impart to the body wall a permanent set substantially that of the true diameter of the container thereby reforming the out-of-round container into a truly round container, and means for shifting said rollers out of operative position by moving them away from said driving and truing wheels for the introduction of a container to be trued and for the discharge of a trued container.
